Primary Examiner — Marianne Pandozzi*Assistant Examiner* — Jae Liang(74) *Attorney, Agent, or Firm* — Greenblum & Bernstein, P.L.C.(57) **CLAIM**

The ornamental design for a mug cover, as shown and described.

DESCRIPTION

FIG. 1 is a isometric view of a mug cover showing my new design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is a top perspective view of FIG. 1 in use on a mug.

The broken line showing in the figure drawings are included for the purpose of illustration and form no part of the claimed design.

1 Claim, 8 Drawing Sheets(56)
